UNITED STATES PATENT OFFICE

104,350

DESIGN FOR A COLOGNE BOTTLE OR SIMILAR ARTICLE

Lucien Lelong, Paris, France, assignor to Lucien
Lelong Inc., Chicago, Ill., a corporation of Illinois

Application March 10, 1937, Serial No. 68,101

Term of patent 7 years

To all whom it may concern:

Be it known that I, Lucien Lelong, a citizen of the Republic of France and a resident of the city of Paris, France, have invented a new, original, and ornamental Design for a Cologne Bottle or Similar Article, of which the following is a specification, reference being had to the accompanying drawing, forming a part thereof.

On the drawing:

I claim:

The ornamental design for a cologne bottle or similar article as shown.

LUCIEN LELONG.
